(57) **CLAIM**

The ornamental design for a enclosure for a blender, as shown and described.

DESCRIPTION

FIG. 1 is a top, front, right side perspective view of an enclosure for a blender showing our new design;

FIG. 2 is a right side elevational view thereof, the left side being a mirror image of FIG. 2;

FIG. 3 is a front elevational view thereof;

FIG. 4 is a rear elevational view thereof;

FIG. 5 is a top plan view thereof; and,

FIG. 6 is a bottom plan view thereof.
